(57) **CLAIM**

The ornamental design for packaging for cosmetics as shown and described.

DESCRIPTION

The patent or application file contains at least one drawing executed in color. Copies of this patent or patent application publication with color drawing(s) will be provided by the Office upon request and payment of the necessary fee.

Fig. 1.1 is a rear view of packaging for cosmetics showing the new design;

Fig. 1.2 is an exploded rear view thereof;

Fig. 1.3 is a bottom view thereof;

Fig. 1.4 is a front view thereof;

Fig. 1.5 is a left-side view thereof;

Fig. 1.6 is an exploded left-side view thereof;

Fig. 1.7 is a front perspective view thereof;

Fig. 1.8 is an exploded front perspective view thereof;

Fig. 1.9 is a right-side view thereof;

Fig. 1.10 is an exploded side view thereof;

Fig. 1.11 is a top view thereof;

Fig. 1.12 is a top view thereof in an open state;

Fig. 2.1 is a front view of packaging for cosmetics showing another embodiment of the new design;

Fig. 2.2 is an exploded front view thereof;

Fig. 2.3 is a top view thereof;

Fig. 2.4 is a rear view thereof;

Fig. 2.5 is a right-side view thereof;

Fig. 2.6 is an exploded right-side view thereof;

Fig. 2.7 is a perspective view thereof;

Fig. 2.8 is an exploded perspective view thereof;

(Continued)

Fig. 2.9 is a left-side view thereof;
Fig. 2.10 is an exploded left-side view thereof;
Fig. 2.11 is a bottom view thereof.
The portions of the packaging for cosmetics shown inside the red broken lines form no part of the claimed design.
